UNITED STATES PATENT OFFICE.

CHARLES A. BUTCHER, OF EAST PITTSBURGH, PENNSYLVANIA, AND LLOYD F. HUNT, OF LOS ANGELES, CALIFORNIA, ASSIGNEES TO WESTINGHOUSE ELECTRIC & MANUFACTURING COMPANY, A CORPORATION OF PENNSYLVANIA.

TIME-LIMIT RELAY.

Application filed May 28, 1924. Serial No. 716,354.

Our invention relates to time-limit relays and particularly to time-limit relays having a plurality of timing devices.

One object of our invention is to provide a time-limit relay that shall have a plurality of contact members that are separately actuated from a single source of mechanical energy.

Another object of our invention is to provide a relay, of the above-indicated character, in which the various contact members are engaged in definite intervals of time in response to predetermined conditions.

A further object of our invention is to provide a relay, of the above-indicated character, in which the intervals of time required for engagement of the various contact members shall be separately adjustable.

A still further object of our invention is to provide a relay, of the above-indicated character, that shall be simple and inexpensive to construct and reliable in its operation.

Our invention comprises, in general, a casing, an electric motor mounted therein, a plurality of contact members and a system of gear trains between the motor and the contact members. A portion of the system of gear trains is movable between two operating positions and, under predetermined conditions, is held by a spring in one of the operating positions. An electromagnet is provided with an armature member that is connected through a system of levers to the movable portion of the system of gear trains for actuating the movable portion into its other operating position against the force of the spring when the electromagnet is energized. When the movable portion of the system of gear trains is held in its first operating position by the spring, the motor is effective to actuate one set of contact members and when it is held in its other operating position, by reason of the energization of the electromagnet, the motor is effective to actuate two other sets of contact members that are adapted to be engaged after respectively predetermined intervals of time after the motor and electromagnet have both been energized.

In the accompanying drawings,

Figure 1 is a front view, partially in elevation and partially in section, of the time-limit relay embodying our invention,

Fig. 2 is a bottom view, partially in plan and partially in section, of the relay shown in Fig. 1,

Fig. 3 is an end view, partially in elevation and partially in section, of the relay shown in Figs. 1 and 2,

Fig. 4 is a detail view of the gear engagement mechanism embodied in our invention, and

Fig. 5 is a detail view of a contact-supporting-disk embodied in our invention.

Referring to the drawings, a driving motor 1 is mounted within a casing 2 and secured in position by screws 3. The motor 1 comprises a shaft 4 that is formed at one end thereof into a pinion 5. The pinion 5 engages a gear wheel 6 that is rigidly mounted on a shaft 7. The shaft 7 is supported by a bracket member 8 that is mounted on and secured to the casing 2 by screws 9.

A bracket member 10 is pivotally mounted on the shaft 7 and provides a mounting for a shaft 11 on which a worm wheel 12 is rigidly mounted. The worm wheel 12 engages a worm 13 that is cut in the shaft 7, thereby establishing a mechanical driving connection between the shaft 4 of the motor 1 and the shaft 11. The lower end of the shaft 11 supports a gear wheel 14 that engages a gear wheel 15 to drive a shaft 16 upon which a pinion 17 is mounted at the lower end thereof. The pinion 17 engages a gear wheel 18 that is mounted on a shaft 19, the lower end of which is supported on a pivot 20 and the upper end 21 of which is supported by a bearing in a bracket member 22.

The shaft 19 carries a contact arm 23 that is provided with a contact member 24 at the outer end thereof, and that is held against a stop member 25 by a spiral spring 26 when the gear wheels 14 and 15 are disengaged. The inner end of the spiral spring 26 is fastened to the shaft 19 and its outer end is held stationary by a clamp member 27. An electrical conductor 28 is connected to the contact member 24 through a bracket member 29 that supports the clamp member 27, the spiral spring 26, the shaft 19 and the contact arm 23.

The contact member 24 is adapted to engage a resiliently mounted contact member 30 when the shaft 19 and the contact arm

23 are turned through a predetermined angle by the pinion 17 co-operating with the gear wheel 18. An electrical conductor 31 is connected to the contact member 30 through a resilient member 32. Thus, when the contact member 24 is actuated into engagement with the contact member 30, electrical connection between the conductors 28 and 31 is effected. The conductors 28 and 31 are connected to terminal members 33 and 34, respectively, that extend through the rear of the casing 2 and are insulated therefrom.

15 A lever arm 35, that is secured to the rear of the bracket member 10 by screws 36, is adapted to be actuated by a lever arm 37 that is connected by screws 40 to an armature member 38 of an electromagnet 39. The opposite end of the lever arm 35 from 20 that which is engaged by the lever arm 37 is provided with a screw 41 to which one end of a tension spring 42 is connected. The other end of the spring 42 is held stationary by a screw 43 that extends through 25 the casing 2.

When the coil of the electromagnet 39 is deenergized, its armature member 38 is held in the position shown in the drawings by the force of the spring 42 that is transmitted through the lever arms 35 and 37 thereto. The armature member 38 is pivotally mounted on a pin 44 that extends through a supporting member 45 that is mounted on one leg of a U-shaped core member 46 of the electromagnet 39. The core member 46 is secured to the casing 2 by screws 47 and its other leg extends through the coil of the electromagnet 39 and provides a support therefor.

40 Electrical connection to the coil of the electromagnet 39 is made through conductors 48 and 49 that are connected to terminal members 50 and 51, respectively. The terminal members 50 and 51 extend through the rear of the casing 2 and are insulated therefrom. A conductor 52 is also connected to the terminal member 50 and extends to one terminal of the windings of the motor 1. The other terminal of these windings is connected through a conductor 53 to a terminal member 54 that is mounted in a similar manner to the terminal member 50.

When the coil of the electromagnet 39 is energized, the armature member 38 is attracted toward the core member 46 to actuate the bracket member 10 and the shaft 11 through the lever arms 37 and 35 against the force of the spiral spring 42. When the shaft 11 is so actuated, a worm 55 that is cut therein engages a worm wheel 56 that is rigidly mounted on a shaft 57. The shaft 57 is supported at one end thereof by a bracket member 58 that is secured to the casing 2 by screws 59.

65 The other end of the shaft 57 extends

into an opening in a member 60 that is supported by a bracket member 61. The bracket member 61 is similar to the bracket member 58 and is secured to the casing 2 by screws 62. One end of the member 60 is provided with a flange 63 that fits in an opening in an insulated disk 64 and the other end thereof is provided with screw threads to receive a nut 65. When the nut 65 is tightened upon the member 60, the insulating disk 64 is clamped against a collar member 66 between it and the bracket member 61.

70 A second insulating disk 67 of the same size as the disk 64 is rigidly mounted on the shaft 57 by means of screws 68, a hub member 69 and a pin 70. The inner end of a spiral spring 71 is secured to the member 60 and the outer end thereof is held in a slot in the head of a screw 72 that extends 75 through a disk 67 and is secured thereto by a nut 73. The force exerted by the spring 71 on the disk 67 may be varied by loosening the nut 65 and turning the member 60, for which purpose a slot 74 is provided. A 80 bracket member 75, supporting two electrically connected contact members 76, is mounted on the circumference of the disk 67. A stop member 77 is similarly mounted on the circumference of the disk 64, but is 85 adjustable with respect thereto by means of a slot 78 and screws 79.

90 A contact member 80 is also mounted on the circumference of the disk 67 by screws 81 and is provided with legs 82 and 83 that 100 are adapted to engage contact members 84 and 85, respectively, when the disk 67 bears a predetermined angular relation to the disk 64. The contact members 84 and 85 are electrically connected through conductors 86 and 87 to terminal members 88 and 89, respectively, extending through the back 105 of the casing 2 and are insulated therefrom.

95 Contact members 90 and 91 are mounted at the ends of resilient members 92 and 93, respectively, the other ends of which are supported by an insulating member 94. The insulating member 94 is supported by a bracket member 95 that is secured to the back of the casing 2 by screws 96. The contact members 90 and 91 are adapted to be engaged by the contact members 76 when the shaft 57 and the disk 67 that is mounted thereon, are turned through a predetermined angle from the position shown in the diagram, which corresponds to the de-energized condition of the motor 1 and the coil of the electromagnet 39.

110 When the contact members 90 and 91 are so engaged, electrical connection is effected 115 between conductors 97 and 98 that are connected at one end to the contact members 90 and 91, respectively, and at the opposite ends thereof to terminal members 99 and 100. The terminal members 99 and 100 are 120 125 130

mounted in a similar manner to that previously described for the other terminal members. The terminal members 50, 54, 99 and 100 are adapted to serve also as mounting bolts for securing the casing 2 to a switchboard.

A cover 101 which may be either of glass or other material, is provided to protect the mechanism of the relay from dust, etc. The cover 101 is fitted to the edge of the casing 2 and is held in place by thumb nuts 102 that screw onto rods 103. The rods 103 extend through holes in the cover 101 and are threaded into bosses 104 that are integral 15 with the casing 2.

The time-limit relay embodying our invention is particularly applicable to automatic substation equipments comprising a synchronous converter for translating energy between an alternating-current supply circuit and a direct-current distribution circuit. Our relay is diagrammatically shown and briefly described for such an application in the co-pending application of Roy J. 20 Wensley, Serial No. 655,842, pneumatically operated stations, filed October 1, 1923, and assigned to the Westinghouse Electric & Manufacturing Company. The circuits used in practicing our invention are shown in 25 detail in this application.

The motor 1 is adapted to be started when a source of electrical energy is connected to the terminal members 50 and 54 of the relay embodying our invention in response to an 30 abnormal condition in a distribution system, such as low voltage across a distribution circuit (not shown), to which the relay is connected. Under these conditions, the coil of the electromagnet 39 is not energized 35 and, consequently, the spring 42 is effective to maintain engagement between the gear wheels 14 and 15.

Therefore, if the motor 1 is energized for a sufficient interval of time, by reason of 40 the prevalence of the above-mentioned abnormal condition, the contact member 24 will be actuated into engagement with the contact member 30, because of the operation of the gear trains previously described. 45 When the contact member 24 engages the contact member 30, a circuit is completed between the terminal members 33 and 34, which are adapted to be connected in circuit with other controlling means.

50 As soon as the last-mentioned controlling means are rendered effective in response to engagement of the contact members 24 and 30, a circuit is completed externally for causing the coil of the electromagnet 39 to be energized. The gear wheel 14 is thereupon actuated out of engagement with the gear wheel 15 and the worm 55 on the shaft 11 is actuated into engagement with the worm wheel 56.

55 When the gear wheel 14 disengages the

gear wheel 15, the spiral spring 26 becomes effective to return the contact arm 23 to its original position against the stop member 25. When the worm 55 engages the worm wheel 56 the shaft 57 and the disk 67 that 60 is mounted thereon are turned by the motor 1 through the gear trains previously described. The circuits for maintaining this condition are maintained until predetermined conditions are attained in the other 65 controlling means. When these conditions are attained, the motor 1 and the coil of the electromagnet 39 are de-energized to permit the worm 55 to disengage the worm wheel 56. The disk 67 and the shaft 57 are 70 thereupon returned to their original positions in which the bracket member 75 engages the stop member 77, because of the action of the spiral spring 71.

If the last-mentioned predetermined conditions are attained within an interval of time that is less than that required for the legs 82 and 83 of the contact member 80 to be actuated into engagement with the contact members 84 and 85, respectively, the relay embodying our invention is rendered ineffective for the time being. In the event, however, that these conditions are not attained before the contact members 84 and 85 are so engaged, it is indicated that certain conditions exist, because of which it is desired to accomplish a certain result.

The contact members 84 and 85 are therefore connected through the conductors 86 and 87 and the terminal members 88 and 89, respectively, to the proper apparatus (not shown) for accomplishing this result. The circuit for effecting this operation is so interlocked with the other controlling means that if the predetermined 105 condition previously mentioned is attained within the predetermined interval of time, engagement of the contact members 84 and 85 thereafter has no effect.

Let it be assumed that the above-mentioned predetermined condition has been attained within the predetermined interval of time allowed therefor. The relay embodying our invention is thereupon rendered ineffective and remains ineffective until another predetermined condition is attained, in response to the prevalence of which for a predetermined interval of time it is desired that another result be accomplished. When such a condition occurs, circuits are completed by the other controlling means to cause the motor 1 and the coil of the electromagnet 39 to be energized.

The disk 67 of the relay embodying our invention thereupon starts to turn in the 125 manner previously described. This operation continues as long as the last-mentioned predetermined condition prevails. If this condition prevails for such an interval of time that it is desired to accomplish the last- 130

mentioned result, the disk 67 will continue to rotate until the contact members 76 engage the contact members 90 and 91. When the contact members 90 and 91 are so engaged, a circuit is thereby completed for accomplishing the desired result. When this result has been accomplished, the motor 1 and the coil of the electromagnet 39 are de-energized to permit the mechanism of our relay to return to its original condition in which it is ready to respond to a repetition of the cycle of events described above.

In the event that the last-mentioned predetermined condition does not prevail for the interval of time that is required for the contact members 76 to be actuated into engagement with the contact members 90 and 91, it is not desired that the last-mentioned result be accomplished. This condition of operation is obtained because the motor 1 and the coil of the electromagnet 39 are de-energized whenever the prevalence of the last-mentioned predetermined condition is interrupted. When such interruption occurs, the worm 55 disengages the worm wheel 56 and the disk 67 is returned to its original position by the action of the spiral spring 71. Thus, the relay embodying our invention is effective to accomplish the last-mentioned result only when the last-mentioned predetermined condition prevails continuously for a predetermined interval of time.

If the condition which causes energization of the motor 1 while the electromagnet 39 is deenergized ceases to exist before the contact members 24 and 30 are engaged, the motor 1 will stop and the movable contact arm 23 will remain in the position to which it has been actuated until the motor 1 is again started, or until the electromagnet 39 is energized. If it is desired that the contact arm 23 be returned to its original position when the motor 1 stops, external means may be provided for momentarily energizing the electromagnet 39. The gear wheel

14 thereupon disengages the gear wheel 15 to permit the spring 26 to return the contact arm 23 to its original position, and the electromagnet 39 may then be deenergized 50 again. It is obvious that this momentary energization of the electromagnet 39 may be accomplished either manually by means of a reset switch or automatically in response to the condition which caused the deenergization 55 of the motor 1.

It will be understood that our invention is not limited to the specific details of construction and connections that have been shown in the drawings and described in the foregoing specification, as many changes and modifications may be made therein without departing from the spirit and scope of our invention, as set forth in the appended claim.

We claim as our invention:

In a time-limit relay, the combination with a source of mechanical energy, a plurality of contact members, and a system of driving means therebetween, comprising: a plurality of trains of gear wheels, one of which trains is permanently connected to the source of energy and others to certain of the contact members, of spring means for effecting engagement between the first-mentioned train and one of the last-mentioned trains to actuate certain of the contact members under predetermined conditions, and magnetic means counteracting the spring means for effecting engagement between the first-mentioned train and another of the last-mentioned trains to actuate certain others of the contact members under other predetermined conditions.
